UNITED STATES PATENT OFFICE.

WILLIAM McCARTY, OF HASKELL, OKLAHOMA.

SPRING PITMAN.

Application filed September 21, 1922. Serial No. 589,695.

To all whom it may concern:

Be it known that I, WILLIAM McCARTY, a citizen of the United States, residing at Haskell, in the county of Muskogee and State 5 of Oklahoma, have invented certain new and useful Improvements in Spring Pitmen; and I do declare the following to be a full, clear, and exact description of the invention, such as will enable others skilled in the art to 10 which it appertains to make and use the same.

This invention relates to an improved pitman for use in connection with machines such as oil well drills and one object of the 15 invention is to provide a pitman which will be a combination rigid and yieldable pitman and will be so constructed that the end sections thereof may be rigidly connected or connected for sliding longitudinally of each 20 other against the action of a coil spring which yieldably holds the end sections against sliding movement.

Another object of the invention is to provide a pitman in which a cushioning spring 25 may be provided to prevent the end sections from striking each other and causing damage when moving under the action of the coil spring which yieldably holds them against movement away from each other.

30 Another object of the invention is to so construct the pitman that the cushioning spring may be coiled about the sliding sections and serve as means to resist side play and thus prevent danger of breakage when 35 the pitman is in use.

Another object of the invention is to provide a pitman which will be simple in construction and can be easily put together and which will be provided with very efficient 40 abutment means for engaging the end portions of the coil spring which yieldably holds the end sections against movement away from each other.

Another object of the invention is to provide a pitman which can be used in connection 45 with a conventional structure of machine with which a pitman is commonly used.

This invention is illustrated in the accompanying drawings, wherein:

Figure 1 is a view in side elevation showing the improved pitman in use.

Figure 2 is a view showing the improved pitman in longitudinal section.

55 Figure 3 is a longitudinal sectional view

through the pitman taken at right angles to the showing in Fig. 2.

This improved pitman is used in connection with a drilling machine which includes a walking beam 1 mounted upon a standard 60 2. A rotatably mounted drive shaft 3 carries a drive wheel or pulley 4 about which passes a belt 5 so that the drive shaft may be rotated from a suitable source of power. The drive shaft carries a crank arm 6 from 65 which extends the wrist pin 7 and the improved pitman will be positioned as shown clearly in Fig. 1 with one end connected with the wrist pin 7 and its second end connected with the walking beam 1 so that as 70 the drive shaft 3 rotates, movement will be imparted to the walking beam.

This pitman is provided with end sections one of which includes a body portion or wrist pin block 8 provided with an opening to receive the wrist pin 7. This block 8 carries side arms 9 which are secured to the block by securing bolts 10. These arms are also provided with openings 11 and 12 for registering with openings 13 and 14 formed 80 in the second end section 15 of the pitman. With the openings in alinement as shown in Fig. 3 securing pins or bolts 13' and 14' can be passed through the alined openings and the two sections will be rigidly connected 85 and thus a rigid pitman provided. With the securing pins removed, the two end sections of the pitman will be slid able longitudinally of each other. It is desired to yieldably hold the two end sections against sliding movement away from each other.

90 Another object of the invention is to provide a pitman which will be simple in construction and can be easily put together and which will be provided with very efficient 95 abutment means for engaging the end portions of the coil spring which yieldably holds the end sections against movement away from each other.

Another object of the invention is to provide a pitman which can be used in connection 100 with a conventional structure of machine with which a pitman is commonly used.

105 Figure 1 is a view in side elevation showing the improved pitman in use.

Figure 2 is a view showing the improved pitman in longitudinal section.

110 Figure 3 is a longitudinal sectional view

spring 16 is strong enough for the work to be performed. If desired, caps 29 may be provided to engage the ends of the springs. A yoke or bail 21 is secured upon the end section 15 by securing bolts 21' and will fit into a notch 22 formed in the walking beam 1 so that the bail cannot move longitudinally upon the walking beam and thus move out of the proper position upon this beam.

When this pitman is in use, it is mounted as shown in Fig. 1 and when the drive shaft 3 is rotating, the pitman will be moved longitudinally and will impart rocking movement to the walking beam. If the two end sections are held against sliding movement, a rigid pitman will be provided but if the securing pins are removed, the two end sections will be free and may have movement longitudinally of each other. It will thus be seen that there will be provided a yieldable or spring pitman. The springs 16 and 16' will yieldably hold the end sections against movement away from each other but will permit these two sections to have the necessary amount of movement. When strain upon the two end sections is removed and the springs 16 and 16' move them longitudinally toward each other, the spring 23 which is positioned between the abutment blocks 18 and shoulders 24 and coiled about the side arms 9, will serve as a bumper to prevent the end sections from striking against each other and thus causing damage. Caps 20 similar to those provided for the springs 16 and 16' may be provided if so desired. In addition to serving as a bumper, the spring 23 also serves as means to resist side play and thus serves as strengthening means to prevent breaking of the arms 9. It will thus be seen that there has been provided a pitman which may be used as a rigid pitman or as a spring pitman. It will be further noted that with this construction, the bolts 10 may be taken out thus releasing the arms 9 and permitting a new spring to be easily put in place in case the spring 16, 16' or 23 should become broken.

I claim:

1. A pitman comprising end sections, one of said end sections including arms slidably extending upon opposite sides of the other end section, a coil spring positioned about the overlapped portions of the end sections, abutments carried by the overlapped portions of the end sections and engaging the spring to yieldably hold the end sections against sliding movement away from each other, removable fasteners passed through the overlapped portions of the end

sections to hold the end sections against sliding movement when the fasteners are in place, and a cushioning spring extending about the arms between the sections and having its ends engaging the sections to limit movement of the sections towards each other.

2. A pitman comprising end sections, one of said end sections including arms slidably extending upon opposite sides of the other end section, fasteners carried by said arms and passing through enlarged openings in the second end section to hold the end sections against transverse movement, a coil spring positioned about the overlapped portions of the end sections, and abutments carried by the overlapped portions of the end sections and engaging the spring to yieldably hold the end sections against sliding movement away from each other.

3. A pitman comprising end sections, one section being provided with arms extending in overlapping relation to the other section, abutments extending from the arms and second section, a spring about the arms and second section and having its ends engaging the abutments, and a spring about the arms and having one end engaging the abutments of the second section, the section carrying the arms having shoulders engaged by the second end of the said second spring.

4. A pitman comprising end sections, one of said end sections having longitudinally extending seats and the second including arms slidably extending upon opposite sides of the other end section and fitting into the seats and held thereby against transverse movement, a coil spring positioned about the overlapped portions of the end sections, and abutments carried by the overlapped portions of the end sections and engaging the spring to yieldably hold the end sections against sliding movement away from each other.

5. A pitman comprising a pair of axially aligned simultaneously movable sections capable of movement toward and from each other, removable means in association with said sections for preventing relative movement thereof, spring means co-acting with said sections for moving them in a direction toward each other when said connecting means is removed, and a cushioning spring co-operative with the adjacent ends of said sections for resisting the action of the first named spring.

In testimony whereof I have hereunto affixed my signature.

WILLIAM McCARTY.
